[57] CLAIM

The ornamental design for a sink, as shown and described.

DESCRIPTION

FIG. 1 is a perspective view taken from the top, front and left side of a sink showing our new design;

FIG. 2 is a top plan view thereof;

FIG. 3 is a cross-sectional view taken on line 3—3 of FIG. 2;

FIG. 4 is a cross-sectional view taken on line 4—4 of FIG. 2;

FIG. 5 is a cross-sectional view taken on line 5—5 of FIG. 2;

FIG. 6 is a perspective view taken from the top, front and left side of a second embodiment thereof;

FIG. 7 is a top plan view thereof;

FIG. 8 is a cross-sectional view taken on line 8—8 of FIG. 7;

FIG. 9 is a cross-sectional view taken on line 9—9 of FIG. 7;

FIG. 10 is a cross-sectional view taken on line 10—10 of FIG. 7;

FIG. 11 is a perspective view taken from the top, front and left side of a third embodiment thereof;

FIG. 12 is a top plan view thereof;

FIG. 13 is a cross-sectional view taken on line 13—13 of FIG. 12;

FIG. 14 is a cross-sectional view taken on line 14—14 of FIG. 12; and,

FIG. 15 is a cross-sectional view taken on line 15—15 of FIG. 12.

The fragmentary broken line representations of counter tops in FIGS. 1, 6 and 11 are for the purpose of illustration only and form no part in the claimed design.
